UNITED STATES PATENT OFFICE

114,321

DESIGN FOR A PRESS

Walter Ernst, Mount Gilead, and Harold Van Doren, Toledo, Ohio, assignors to the Hydraulic Development Corporation, Inc., Wilmington, Del., a corporation of Delaware

Application February 6, 1939, Serial No. 82,798

Term of patent 14 years

To all whom it may concern:

Be it known that we, Walter Ernst and Harold Van Doren, citizens of the United States, residing at Mount Gilead, in the county of Morrow and State of Ohio, and Toledo, in the county of Lucas and State of Ohio, respectively, have invented a new, original, and ornamental Design for a Press, of which the following is a specification, reference being had to the accompanying drawings, forming a part thereof.

In the drawings:

Figure 1 is a perspective showing our new design for a press;

Figure 2 is a front elevation thereof; and

Figure 3 is a side elevation thereof.

We claim:

The ornamental design for a press, as shown.

WALTER ERNST.
HAROLD VAN DOREN.

CERTIFICATE OF CORRECTION.

Design No. 114,321.

April 18, 1939.

WALTER ERNST, ET AL.

It is hereby certified that error appears in the above numbered patent requiring correction as follows: In the heading to the printed specification, lines 4 and 5 thereof, name of assignee, for "the Hydraulic Development Corporation, Inc." read The Hydraulic Development Corporation, Inc.; and that the said Letters Patent should be read with this correction therein that the same may conform to the record of the case in the Patent Office.

Signed and sealed this 22nd day of August, A. D. 1939.
